Ira L. Thresher

UNITED STATES PATENT OFFICE.

CHARLES B. COATES, OF CLEVELAND, OHIO, ASSIGNOR TO CHICAGO PNEUMATIC TOOL COMPANY, OF NEW YORK, N. Y., A CORPORATION OF NEW JERSEY.

SWITCH LOCK.

Application filed August 12, 1924. Serial No. 731,543.

This invention relates to control apparatus for electrical motors and machinery. In particular it concerns automatic locking means operated by one control device or switch to render a second control device or switch inoperative.

One object of the invention is to provide a simple, compact, easily operated control assembly with self contained locking mechanism of the type described. Another object is to make the actuation of the locking mechanism dependent upon the condition of the electrical circuit to be controlled. Other objects will be apparent from the detailed description which follows.

The particular form of the invention used as an illustrative example and disclosed in the accompanying drawings is intended for use on portable electrical tools but is obviously capable of general application and use.

In the drawings:

Fig. 1 is a plan view partly in section on the line 1—1 of Fig. 2;

Fig. 2 is a vertical sectional view on the line 2—2 of Fig. 1 with the main or snap switch shown in elevation and the locking mechanism in operative position;

Fig. 3 is a fragmentary sectional view similar to Fig. 2 but on an enlarged scale and showing the locking mechanism in inoperative position; and

Fig. 4 is a diagrammatic showing of the electrical circuit.

The drawings disclose what is at present believed to be the preferred form of the invention which comprises in general a unit control assembly A provided with a junction or inlet box a with which the power cable a' connects, secured in any suitable or desired manner to the casing or other portion B of the tool, motor, or other electric device to be controlled. The control assembly is housed within a casing consisting of an upper part 5 and a lower part 6, the same being secured together in assembled relation by screw bolts 7 and the lower portion 6 having a flange 8, through openings in which suitable means such as screw bolts 9 may pass to securely attach the control assembly A to the casing B of the machine to be controlled. The casing contains a plurality of control elements or switches, in the present instance, two in number, a main switch 10 and a reversing switch 11. The reversing switch 11 may be

of any suitable or desired type, that shown having a control handle 12 projecting from one side of assembly A and pivoted at 13 for limited swinging movement. Switch 11 is by preference disposed within the lower part 6 of the casing. The main switch 10, which is by preference disposed in the upper part 5 of the casing, may be, and preferably is of the ordinary type of snap switch which being simple, compact and efficient lends itself well to incorporation in a control assembly of this type.

In order to properly house the locking mechanism for the reversing switch, which forms an important feature of the present invention, parts 5 and 6 of the switch assembly casing have extensions 5^a and 6^a disposed above the path of movement control handle 12. These extensions have opposed registering recesses to receive the locking mechanism now to be described.

Lower casing extensions 6^a supports for reciprocal movement a locking pin 14 slidably mounted in a socket 6^b and arranged to extend across the path of movement of switch handle 12 to prevent throwing of the same. A coil spring 15, acting against the head of the pin, holds the latter in its upper retracted or inoperative position (Fig. 3) when the main switch is "off". Pin 14 has an extension 14^a of magnetizable material, the upper end of which is received in a socket in a projection 5^b of the upper portion of the casing when the pin is in unlocked position (Fig. 3). A solenoid coil 16 encircling pin extension 14^a is seated in the recessed portions of the casing extensions 5^a and 6^a. This coil carries a core 17 arranged magnetically to affect the extension 14^a of the locking pin. The parts forming core 17 may extend outwardly beyond the coil 16 and be partly housed in opposed recesses or grooves 18 in the casing extensions 5^a and 6^a (Fig. 1). For use with direct current the pin extension 14^a and the core 17 may be of solid material such as soft iron, but when alternating current only is available better results are secured by making these parts of laminated material, as shown in the drawings, the plates of the laminar core 17 being preferably disposed in line with the plates of the laminar extension 14^a of the locking pin.

The electrical connections are such that when the main or snap switch 10 is actu-

ated by its button 10^a to the "on" position (Figs. 1 and 2), the electrical current is passed through the solenoid coil 16 magnetizing the laminar core or plates 17 there-
 5 of and drawing the pin extension 14^a by magnetic attraction to its lower position (Fig. 2), wherein the locking pin 14 is projected across the path of the reverse handle 12 and prevents the reversing of the electric-
 10 machine. When the main switch button 10^a is turned to the "off" position, the current ceases to flow through the coil 16, the core 17 loses its magnetism, and the spring 15 restores the locking pin 14 and its exten-
 15 sion 14^a to its upper inoperative or unlock-
 ing position (Fig. 3).

One arrangement of the circuit is dia-
 grammatically illustrated in Fig. 4, wherein
 20 main switch 10 is shown open and the re-
 verse handle 12 in neutral position. Assuming
 the reverse handle 12 moved to the left
 and switch 10 closed the circuit leads from
 25 the positive terminal through connection *c*,
 switch 10, connection *d*, solenoid coil 16,
 connection *e*, terminal *f*, wiper *g* on the re-
 verse handle, connection *h*, the motor arma-
 ture, connection *i*, wiper *g'* on the reverse
 30 handle, terminal *j*, connection *k*, terminal *j'*,
 connection *l*, the field of the motor, connec-
 35 tion *m*, to the negative terminal. To re-
 verse the motor, switch 10 is opened where-
 upon locking pin 14 is retracted as described
 above and reverse handle 12 is moved to
 40 the right, whereupon on closing switch 10
 the circuit connection is as follows: connec-
 tion *c*, switch 10, connection *d*, solenoid coil
 45 16, connection *e*, terminal *f*, wiper *g'*, connec-
 tion *i*, the armature of the motor, connec-
 tion *h*, wiper *g*, terminal *j'*, connection *l*,
 the field of the motor and connection *m*.
 Thus the closing of the main switch in either
 50 operative position of the reverse handle 12
 sends current through the solenoid coil 16
 to force and hold locking pin 14 in its lock-
 ing position until the main switch is open.

As the parts of the locking mechanism
 and the connections thereto are entirely en-
 closed within the casing of the control as-
 55 sembly which exposes only the main switch
 button 10^a and the reversing handle 12,
 there is no opportunity for the operator to
 tamper with the mechanism and prevent its
 operation. Thus reversing of the motor
 60 while the main switch is "on" is effectively
 prevented and possible injury to the opera-
 tor and inevitable damage to the motor re-
 sulting from such lack of intelligent control
 is entirely avoided.

I claim as my invention:

60 1. The combination with a portable elec-
 trically operated machine of control appa-
 ratus secured to a portion of the machine
 comprising a casing in two parts, a control
 switch in each of said parts, said parts hav-
 65 ing opposed recesses adjacent the control

handle of one of said switches, and a sole-
 noid mounted in said recesses and control-
 ling a locking pin for said control handle.

2. In electrical control apparatus, in com-
 bination, a casing in two parts, a control 70
 switch in each of said parts, said parts hav-
 ing opposed recesses adjacent the control
 handle of one of said switches, a locking
 pin disposed in said recesses and arranged
 to be projected across the path of movement 75
 of said control handle, and electrical means
 under control of the other switch for con-
 trolling said pin.

3. The combination with a portable elec-
 trically operated machine of control appa- 80
 ratus therefor comprising a casing secured
 to a portion of the machine, control switches
 therein, said casing having a recess adjacent
 the control handle of one of said switches,
 a locking pin in said recess normally held 85
 out of the path of movement of said con-
 trol handle, and electrical means also within
 said recess and under control of the other
 switch for projecting said pin into the path
 of said control handle to lock the same 90
 against movement.

4. In electrical control apparatus, in com-
 bination, a casing in two parts, a control 95
 switch in each of said parts, said parts hav-
 ing opposed recesses adjacent the control
 handle of one of said switches, a locking pin
 in said recesses, resilient means yieldingly
 maintaining said pin out of the path of 100
 movement of said control handle, and a
 solenoid coil within said recesses and en-
 circling an extension of said pin for mov-
 ing the latter against said resilient means
 to locking position.

5. In electrical control apparatus, in com-
 bination, a casing in two parts, a snap 105
 switch in the upper part and a reversing
 switch in the lower part, the latter having
 a projecting handle, extensions on both said
 parts of the casing above said handle, said
 parts having opposed registering recesses in
 110 their said extensions, a locking pin in the
 recess of said lower part, a spring normally
 holding said pin out of the path of move-
 ment of said handle, an extension on said
 pin, a solenoid coil disposed in said recesses
 115 and encircling said pin extension, and a
 core supported by said coil in operative re-
 lation to said extension, said coil being un-
 der control of said snap switch for project-
 ing the locking pin into locking position
 120 when the snap switch is "on".

6. In electrical control apparatus, in com-
 bination, a casing in two parts, a snap 125
 switch in the upper part and a reversing
 switch in the lower part, the latter having
 a projecting handle, extensions on both said
 parts of the casing above said handle, said
 parts having opposed registering recesses in
 130 their said extensions, a locking pin in a
 socket of said lower part adjacent its recess,

a spring in said socket normally holding said pin out of the path of movement of said handle, a laminar extension on said pin, a solenoid coil disposed in said recesses and 5 encircling said pin extension, and a laminar core supported by said coil with its plates in line with the plates of the laminar extension of said pin, said coil plates being

partly received in opposed grooves in said casing parts adjacent said recesses, said coil 10 being under control of said snap switch for projecting the locking pin into locking position when the snap switch is "on".

Signed by me at Cleveland, Ohio, this 5th day of August 1924.

CHARLES B. COATES.
